CLAIM

The ornamental design for a cover for vehicle seat headrest, as shown and described.

DESCRIPTION

FIG. 1 is a perspective view of a cover for a vehicle seat headrest showing my new design;

FIG. 2 is a front view thereof; and,

FIG. 3 is top plan view thereof.

The broken line showing a headrest covering and draw strings is for illustrative purposes only and forms no part of the claimed design.

1 Claim, 1 Drawing Sheet

FIG. 3
